US00D476563S

(12) **United States Design Patent** (10) Patent No.: **US D476,563 S**
Brozell et al. (45) Date of Patent: ** Jul. 1, 2003

(54) **SQUEEZE-AND-TURN CHILD RESISTANT CLOSURE**

Primary Examiner—Louis S. Zarfas
Assistant Examiner—Gregory Andoll

(75) Inventors: **Brian J. Brozell**, Maumee, OH (US);
Stephen A. Eilertson, Perrysburg, OH (US); **Philip J. Robinson**, Sylvania, OH (US)

(57) **CLAIM**

We claim the ornamental design for a squeeze-and-turn child resistant closure, as shown and described.

(73) Assignee: **Owens-Illinois Closure Inc.**, Toledo, OH (US)

DESCRIPTION

(**) Term: **14 Years**

(21) Appl. No.: **29/167,174**

FIG. 1 is a perspective view of a squeeze-and-turn child resistant closure in accordance with one exemplary presently preferred embodiment of the invention;

(22) Filed: **Sep. 9, 2002**

FIG. 2 is a top plan view of the closure, the bottom of the closure being without ornamentation and forming no part of the claimed design;

(51) LOC (7) Cl. **07-09**

FIG. 3 is a side elevational view from the bottom in FIG. 2, the opposing side elevational view being substantially a mirror image thereof;

(52) U.S. Cl. **D9/435**; D9/454; D9/453;

FIG. 4 is a side elevational view taken from the right in FIG. 3, the opposing side elevational view being substantially a mirror image thereof;

D9/452; D9/443

FIG. 5 is a perspective view of a squeeze-and-turn child resistant closure in accordance with a second exemplary embodiment of the invention, the top plan view of which is substantially the same as FIG. 2 and the bottom being without ornamentation and forming no part of the claimed design;

(58) Field of Search D9/435, 443, 445,

FIG. 6 is a side elevational view of the closure in FIG. 5, the opposing side elevational view being substantially a mirror image thereof; and,

D9/452, 453, 454; 215/216, 217, 218, 219,
206

FIG. 7 is an end elevational view of the closure in FIGS. 5-6, the opposing end elevational view being substantially a mirror image thereof.
